PLASTIC SPINE CONSTRUCTION FOR BOOKS
Sydney H. Dengle and William McKown, Des Moines,
Iowa, assignors to Meredith Publishing Company, Des
Moines, Iowa, a corporation of Iowa
Filed Aug. 6, 1962, Ser. No. 215,127
6 Claims. (Cl. 281—29)

This invention relates to a plastic spine construction for books of the permanently bound type.

One object of our present invention is to provide a spine construction comprising outer and inner spine members which are secured together with a back member of page covers interposed between them, the pages of the book being adhesively secured to a fabric element on the inside of the inner spine member which has portions passing around the side edges of the inner spine member and interposed between the outer surface thereof and the back member of the page covers whereby the expense of fabrication when compared with Smyth sewn books is substantially less, yet quality and durability of the book are substantially increased.

Another object is to provide the spine members secured together by a post-and-perforation arrangement wherein a connecting post has a head which snaps through a perforation to provide a permanent connection between the spine members.

Still another object is to provide page covers and a flexible back member connecting them together, such back member being interposed between the spine members.

A further object is to provide side flanges along the outer spine member which overlap the side edges of the inner spine member, and confine between such edges and the flanges that portion of the back member that extends from the spine members to the back edges of the page covers and serves as a hinge means for the page covers.

Still a further object is to provide a fabric element partially or completely surrounding the inner spine member to which the pages of the book are adhesively secured and which gives a superior opening action for the pages of the book after the same is assembled.

An additional object is to provide a modified form of construction in which (instead of the posts and perforations) the outer spine member has channel-shaped flanges along its side edges to overlap and partially enclose the side edges of the inner spine member to thereby retain the parts of the spine construction assembled, spots of adhesive being used advantageously between certain surfaces of the spine construction to prevent undesirable longitudinal movement of one spine member relative to the other and/or to any part of the bound book.

With these and other objects in view, our invention consists in the construction, arrangement and combination of the various parts of our plastic spine construction for books, whereby the objects above contemplated are attained, as hereinafter more fully set forth, pointed out in our claims and illustrated in detail on the accompanying drawings wherein:

FIG. 1 is a perspective view of a book including our plastic spine construction;

FIG. 2 is an enlarged sectional view thereof on the line 2—2 of FIG. 1;

FIG. 2a is a sectional view similar to a portion of FIG. 2 showing a modified construction;

FIG. 2b is a perspective view of a portion of such modification;

FIG. 3 is a reduced sectional view showing the parts separated from each other to illustrate the assembly thereof together;

2

FIGS. 4, 5, 6 and 7 are unsectioned diagrammatic views similar to FIG. 3 showing four steps of the assembly, the fifth step being illustrated in FIG. 2;

FIG. 8 is an end elevation of a book including our spine construction and illustrating the way the leaves lie flat when the book is open; and

FIG. 9 is a sectional view similar to FIG. 2 showing a modified construction.

On the accompanying drawings we have used the reference numeral 10 to indicate the pages of a book and 12 the page covers thereof. An outer spine member 14 and an inner spine member 20 are provided formed of plastic material such as polypropylene, polystyrene, nylon, delrin or the like. The outer spine member 14 is molded 15 with side flanges 16 and post-like projections 18 terminating in heads 26 as shown in FIG. 2, and the inner spine member 20 is molded with perforations 22 having counterbored portions 24. Four or five of the projections 18 and likewise four or five of the perforations 22 are 20 spaced along the backbone of the book, this number being sufficient as a connecting means between the two spine members for the average size book.

The page covers 12 may comprise binder boards 28 covered outside with fabric or paper 30 and inside with 25 fabric or paper 32 (which may be double-thickness as shown only in FIG. 2). The arrangement is such that the fabric or paper 30 and 32 extend between the spine members 14 and 20 for anchoring the page covers to the spine of the book and to provide hinging means for 30 the page covers between the left hand edges of the binder boards 28 shown in FIG. 2 and the right hand edges of the flanges 16.

Page mounting means in the form of a strip of fabric 34 is provided which as shown in FIG. 3 has a layer of 35 adhesive 36 centrally on one side thereof and two strips of adhesive 38 (also shown in FIG. 4) on the opposite side thereof. The curvature of the outer spine member; 14 is sharper than the curvature of the inner spine member 20, as will be seen in FIG. 3, for a purpose to hereinafter appear.

The parts of the spine construction are assembled as 45 illustrated in FIGS. 3 to 7, FIG. 3 showing the general assembly and FIGS. 4 to 7 the steps. The first step as shown in FIG. 4 consists of melting the adhesive 36 by heat and securing the inner edges of the pages 10 to the fabric 34 in a suitable press, after which the second step 50 consists of wrapping the outer flanges of the fabric 34 around behind the back of the inner spine member 20 and adhesively securing them thereto as shown in FIG. 5, the glue strips 38 being heated for this purpose and the 55 glue between the fabric and the pages, and between the fabric and the back of the inner spine member, being illustrated by means of stippling 36a and 38a respectively in FIGS. 4, 5, 6 and 7.

Next the back member comprising the elements 30 and 32 (after the binder boards 28 have been assembled therein) are wrapped around the back of the inner spine member as shown in FIG. 6 and the assembly is ready to receive the outer spine member 14. This is brought to the 60 position shown in FIG. 7, the inwardly inclined flanges 16 being sprung over the edges of the inner spine member as illustrated, and the head 26 brought to engagement with the inner wall of the perforation 22 of the inner spine member. Thereafter pressure is applied in one direction 65 to the pages of the book along the plane thereof and in the opposite direction to the outer spine member to force the heads 26 through the perforations 22 until they snap into the counterbores 24 as shown in FIG. 2 which is the 70 final assembled position.

Since the curvature of the outer spine member is sharper than the curvature of the inner spine member, by com-

paring FIG. 2 with FIG. 7 it will be realized that the curvature of the outer spine member has been made flatter in FIG. 2, and that of the inner spine member sharper until they conform with each other thus applying the desired clamping pressure to the assembly along the outer margins of the spine members as well as along the center where the posts and perforations provide the desired pressure when snapped together. Subsequently when the book is opened as in FIG. 8, the fabric 34 will readily bend away from the inner surface of the inner spine member 20 as illustrated in FIG. 8 and permit the book to "lie flat." This is one of the main advantages of adhesively securing the pages of the book to the fabric 34 and associating the fabric with a curved inner spine member as disclosed.

In the modification shown in FIG. 2a, a sheet metal inner spine member 20a replaces the plastic spine member 20, and the posts 18a of the outer spine member 14a are headless. The perforations 22a are slightly smaller in diameter than the posts, and are so constructed and arranged in the area immediately surrounding the perforations as to permit insertion of the posts but prevent their removal whereby the spine members are locked together. The area referred to may for example be cone shaped as shown in FIG. 2b and provided with slits 23 in the manner of a "Tinnerman" fastener. Some of the heavier books require greater holding power than afforded by the all plastic construction of FIG. 2 and this may be accomplished by the FIG. 2a construction wherein the edges of the opening 22a, due to the cone shape shown in FIG. 2b, permit the post 18a to be readily inserted but thereafter "bite" into the surface of the post upon any reverse movement of the post.

In the modification shown in FIG. 9 the posts 18 and the perforations 22 are omitted, and the outer and inner spine members illustrated and referred to as 14a and 20a may be of substantially the same curvature in relation to each other. Instead of the flanges 16 illustrated in FIGS. 2 and 3, however, channel-shaped flanges 16a are provided and serve to partially enclose the edges of the inner spine member 20a to effect assembly by longitudinal sliding of the outer spine member 14a over the assembly of inner spine member 20a, fabric tube 34a and back member 30-32.

In this instance the fabric page mounting means 34a is in the form of a tube completely surrounding the inner spine member, and to prevent undesirable longitudinal movement of the spine members relative to each other and relative to the back member of the book, spaced spots of adhesive 40, 42 and 44 are provided between the tube 34a and the inner spine member 20a, between the tube 34 and the back member element 32, and between the back member element 30 and the outer spine member 14a respectively. The final assembly of the modified construction shown in FIG. 9 results in a book that opens and lies flat in substantially the same manner as already described in connection with FIGS. 1 to 8 inclusive.

Some changes may be made in the construction and arrangement of the parts of our plastic spine construction without departing from the real spirit and purpose of our invention, and it is our intention to cover by our claims any modified forms of structure or use of mechanical equivalents which may reasonably be included within their scope.

We claim as our invention:

1. In a spine construction for books, a curved outer spine member, a curved inner spine member, a fabric element inside said inner spine member and at least partially around the outside thereof, book pages adhesively secured to that portion of said fabric element on the inside of said inner spine member, that portion of said fabric element on the outside of said inner spine member being adhesively secured to said outside thereof, page covers having a back member interposed between said spine members, and means for holding said spine members assembled on opposite sides of said back member.

2. The spine construction of claim 1 wherein said last means comprises integral headed connecting posts on one of said spine members, the other of said spine members having perforations to receive said posts, said perforations being slightly smaller than the heads of said posts to require forcing therethrough whereby a permanent connection of said spine members to each other is effected.

3. The spine construction of claim 1 wherein said inner spine member is formed of metal and said last means comprises integral connecting posts on said outer spine member, said inner spine member having perforations slightly smaller in diameter than said posts which are so constructed and arranged in the area immediately surrounding said perforations as to permit the insertion of said posts therethrough but prevent their withdrawal therefrom whereby said spine members are locked together.

4. The spine construction of claim 1 wherein said spine members are curved, said inner spine member before assembly being flatter in curvature than said outer spine member and said posts being substantially centrally located between the side edges of the spine members whereby said side edges exert pressure toward each other after assembly and squeeze said back member between them.

5. In a spine construction for books, an outer spine member formed of plastic material, an inner spine member, said spine members being curved and the curve of the outer one being sharper than the curve of the inner one, a fabric element inside said inner spine member and at least partially around the outside thereof, book pages adhesively secured to that portion of said fabric element on the inside of said inner spine member, page covers having a back member interposed between said spine members, and means along the center of said spine members for securing them together, said means extending through said back member and drawing the outer surface of said fabric element and the inner surface of said outer spine member into contact with the inner and outer surfaces of said back member.

6. The spine construction of claim 5 wherein said last means comprises integral headed connecting posts on one of said spine members, the other of said spine members having perforations to receive said posts, said perforations being slightly smaller than the heads of said posts to require forcing therethrough to provide a permanent type connection.
